ELECTRON DISCHARGE DEVICE

Charles W. Taylor, East Orange, N. J., assignor,
by mesne assignments, to Radio Corporation of
America, New York, N. Y., a corporation of
Delaware

Application January 22, 1935, Serial No. 2,870

11 Claims. (Cl. 250—27.5)

My invention relates to thermionic discharge devices and more particularly to electrode assemblies and their supporting means within the tube.

The object of my invention is to provide a 5 mount assembly of the unit type of construction which is easily assembled, rugged in construction, and has good electrical characteristics. According to my invention an electrode assembly is so related to a shielding arrangement that a 10 mechanically rugged tube is produced which has particularly desirable electrical characteristics. A better understanding of my invention may be had by reference to the accompanying drawing in which Figure 1 is a perspective view of one 15 form of the tube embodying my invention with some of the elements cut away to show the electrode assembly, and Figure 2 is a perspective view showing the outside of the mount.

Referring to Figure 1 a conventional form of 20 bulb is shown at 1 with contact cap 2, base 3 and the usual reentrant stem 4 the upper end of which is a press or seal 5 in which the various lead-in wires are embedded. Upon the stem is supported an electrode assembly of the unit 25 mount construction in which a pair of parallel equipotential cathodes 6, a control grid 7, a screen grid 8, a suppressor grid 9 and an anode 10 are mounted between two insulating bars or spacers 11 and 12. The spacer bars 11 and 12, which 30 preferably are of a ceramic material, such as lavite, are secured in fixed spaced relation by side rods which pass thru the spacers and thru sleeves in the sides of anode 10. The grids are of the usual double helical side rod construction with 35 the side rods 13 which extend into small holes in the spacer bars. The anode is connected by a lead 14 to the top cap 2, the screen grid 8 by a lead 15 passing thru the side of the stem tube to a contact pin in the base 3, and the other electrodes are connected to the leading-in wires in the press to the other contact pins on the base.

As distinguished from the usual prior art construction in which the electrode assembly is mounted directly upon the stem and press, my 40 device is provided with a combination supporting and shielding arrangement in which a tubular shield 16, which surrounds the press and lead-in wires, is supported by the stem thru curved supporting rods 17 and is conveniently secured to 45 the stem by embedding the inner ends of the rods in the press. This shield is reduced in diameter at the upper end to be slightly smaller than the lower spacer, and has a shoulder or offset portion 18 and upwardly extending flange 19. The lower 50 spacer rests upon the upper edges of flanges 19, 55

so that the shield supports the electrode assembly. The shielding member 16 supports the electrode assembly on the stem, thereby relieving the leading-in wires of mechanical strains, and also electrically shielding the leading-in wires of the 5 stem.

On the upper surface of the upper insulating spacer 12 is a disc 20, preferably of mica, which is clinched under the welded tabs at the upper ends of the plate side rods as shown. The mica disc is 10 cut away at the center as at 21 as best shown in Figure 2, to provide a central recess which spaces the mica from all of the side rods projecting thru the ceramic spacer 12. Over this central recess an oblong concave shield 22 is positioned and is 15 clinched in place by a strap 23 which extends across the mica disc. In order that the electrode assembly may be securely clamped to the upper edges of the lower shield, the outer ends of said strap are welded or otherwise secured to the upper ends of two tie rods 24 and 25, which pass 20 downwardly thru holes in the mica disc and are welded or otherwise fastened to shield 16. It will be seen that by securing the lower ends of these tie rods to the lower shield all of the elements 25 between the upper shield 22 and lower shield 16 are securely clamped together into a very rigid structure. To resiliently but firmly center the mount structure within the dome of the bulb of the tube, the mica disc 20 may be provided with mica spacers 26, such as disclosed in U. S. Patent 2,058,790 30 dated October 27, 1936 and filed by Hirman on November 11, 1933 and assigned to Radio Corporation of America. By this construction I have provided a unitary assembly of electrodes and 35 shields which are clamped against longitudinal displacement and which are accurately and firmly centered within the envelope.

Very complete shielding is afforded by this 40 construction as the lower shield 16 protects the leads in the press from high frequency field effects, and the shielding may, if desired, be virtually extended to the very end of the outside grid 9 by a collar 27 having depending flange 28. Collar 27 is of rectangular form, welded at its ends to side 45 rods of the outer grid, the sides of which are extended to form a flange as shown at 28. It may be noted that since flanges 19 of the lower shield are set inwardly from the edge of the spacer, said shield and collar are out of electrical contact. I 50 may also provide at the upper end of grid 9 and supported upon its side rods a second shielding collar 29 with its flange 30, which extends to the lower side of the mica disc, and is separated from the upper shield only by the thickness of the mica 55

disc. The upper shield 22 effectively protects the upper ends of the grid side rods and of the cathodes from any high frequency field effects from the anode lead. The only exposure, therefore, of the inner electrodes to high frequency field effects from plate 10 is laterally thru the meshes of the screen grid 8. I have found in practice that this shielding arrangement substantially eliminates all back coupling between input and output electrodes even at such high frequencies as 60 megacycles.

For some applications of my tube I prefer to provide an electrical connection from the lower shield support rod 17 to a contact pin in the base 15 of the tube, so that any desired potential may be applied to the lower shield 16 and its connected upper shield 22.

According to a further feature of my invention the anode 10 is formed of dark surfaced 20 metal such as carbonized nickel while the top and bottom shields are formed of polished material such as nickel or molybdenum. However, some difficulties may be encountered in the high frequency heat treatment during exhaust unless 25 the structure is somewhat modified. The principal difficulty in manufacture was found to be the uneven heating of the carbonized nickel with respect to the polished nickel, which apparently is due to the difference in the heat absorption 30 and radiating properties of the two metals. It was found in practice that the temperature of the dark anode could not be raised to the proper value before the temperature of the shields reached a dangerously high value. To overcome 35 this difficulty and in accordance with my invention I make the shields smaller in cross section than the anode and as a result of the reduced cross sectional dimensions of the shields with respect to those of the anode the reduced shields 40 cut fewer lines of force from the high frequency heating coil placed about the tube than does the anode, thus reducing the heating of the shields.

It has been found that a carbonized electrode 45 when placed adjacent or directly on the spacer bars of the mount assembly, causes the deposit of a considerable amount of conductive particles on the surfaces of the spacers, thus resulting in objectionable leakage paths between electrodes. 50 To overcome this difficulty in my device I space the carbonized electrode, which by way of example may be an anode of carbonized nickel, from the spacer bar by means of collars 31 on the anode side rods. It is found that this arrangement 55 substantially eliminates conductive deposits on the spacer bars. These insulating collars may be formed of ceramic material such for example as aluminum oxide, which has been chosen because of its freedom from conductive particles. 60 Collars 31 possess the further advantage of substantially reducing high frequency heating losses within the tube. In the old construction where the plate comes in direct contact with the spacer bars or where the plate is secured to the 65 spacer bar by a metal strap passed around the spacer bar, considerable energy was found to be dissipated in the spacer bar between the plate and the lower potential electrodes in the spacer bar. I have found that this loss in one tube 70 caused the normal output of 14 watts to drop to 3 watts.

To further insure against conductive deposits on the spacer bars from the carbonized grids, the end turns of the grid are freed of the usual carbon coating.

In addition to providing complete shielding and a rugged construction by my arrangement of shields and electrode assembly I have produced a tube which is easy to manufacture. The electrode assembly is formed as a unit by slipping the 5 lower spacer 11 upon the anode side rods, by threading on the collars 31 and anode 10 and by inserting the grid side rods in their proper holes in the lower spacer. This unit mount construction is finally completed by clamping on the 10 upper spacer and mica disc under the welded tabs at the upper end of the anode side rods. The electrode leads are then connected to their proper contacts in the press and the lower shield 16, which is provided in two halves, is welded to 15 their support rods 17. The fabrication of my mount assembly is completed by strapping the upper shield 22 in place by welding its strap 23 to the clamping rods 24-25, which are finally welded at their lower ends to the lower shield. 20 It will thus be seen that during assembly of the tube according to my invention all welding operations are effected from without the elements of the tube, which eliminates the difficulty of welding in confined spaces.

In the embodiment of my invention shown in the drawing two equipotential cathodes mounted side by side are shown. When operated at ultra high frequency these two parallel cathodes may have an effect much like a tuned lecher wire 30 system at the operating frequency, and hence considerable high frequency energy may be radiated directly from the cathodes. Under these conditions I prefer to connect the upper ends of these cathodes as shown at 32 so as to short circuit 35 any possible standing waves upon the cathodes.

Whereas I have disclosed the preferred embodiment of my invention it is obvious to those skilled in the art that many modifications may be made without departing from the spirit of my invention. It is desired, therefore, that the scope of 40 my invention be limited only by the art and by the appended claims.

Having described my invention, I claim—

1. A thermionic discharge device comprising a 45 reentrant stem with a press with lead-in wires sealed therein, a shield surrounding and mechanically secured to the stem, an electrode assembly of the unit mount construction resting upon the upper edge of said shield, and electrical 50 connections between said electrode assembly and said lead-in wires.

2. A thermionic discharge device comprising an envelope with a re-entrant stem having a press at one end, a shield member surrounding 55 said press and supported by the stem, an electrode assembly of the unit mount construction positioned on and mechanically supported by the shield member.

3. In a thermionic discharge device, a unit 60 mount construction comprising a stem with a press, a thermionic cathode, grid and anode electrodes each having a side rod, two insulating spacers arranged one above the other and recessed to receive the side rods of said electrodes, 65 a shield around the stem and supported by the stem, the upper edge of the shield being arranged to bear against the lower face of the lower spacer, an upper shield positioned over the upper ends of the grid side rods, and connecting means between 70 the upper and lower shields to mechanically and electrically tie the shields together.

4. A thermionic discharge device comprising an envelope and a press, cathode, grid and anode electrodes with side rods concentrically arranged 75

and secured between two ceramic spacers one above the other, said spacers being recessed to receive the side rods of said electrodes, locking means secured to the ends of two of said side rods 5 so as to form a unit mount assembly of the electrodes; a lower shield positioned around the press of the discharge device and supported thereon, the upper edge of the shield being arranged to bear against the lower spacer, a mica disc 10 secured to the upper face of the upper ceramic spacer and clinched under said locking means, said disc being recessed centrally to receive the upper ends of said side rods, an upper shield positioned over said central recess, a strap formed 15 over the upper shield, the ends of the strap being secured mechanically to the lower shield.

5. An electron discharge device comprising a glass stem with a press, support rods extending from said press, said support rods formed with 20 curved portions, a tubular shielding member positioned around said press, means for supporting said member on said press comprising radially extending flanges on said member, said flanges being formed around the curved portions of said 25 support rods to prevent movement of said member on the curved rods.

6. In a thermionic discharge device, a unit mount construction comprising an anode and concentric grid electrodes with side rods, an insulating spacer recessed to receive and hold the 30 ends of said side rods, and a concave shield positioned over and around the ends of the grid side rods.

7. A thermionic discharge device comprising 35 an electrode assembly of the unit mount construction with an insulating spacer bar, side rods inserted at their ends into and thru said spacer bar, electrodes secured to said side rods, a centrally recessed insulating disc secured to the side

of the spacer bar opposite the electrodes, and a concaved shielding means positioned over the recessed portion of said disc to enclose said ends of the side rods.

8. In a unit mount construction, a side rod and 5 a grid mounted on said side rod, an insulating spacer bar, a collar supported by said side rod concentric with said grid, and a depending flange from said collar arranged to cover one edge of 10 said spacer bar.

9. An electron discharge device with a reentrant stem, a press on said stem, a tubular shield surrounding and supported by said press, an insulating spacer supported upon the upper edge of 15 said shield, the edges of said shield being positioned inwardly from the edges of said spacer, a rod, a grid mounted on said rod, an annular collar supported on said rod adjacent one end thereof, said collar resting upon the upper side of 20 said spacer, said collar having a flange extending downwardly over the edge of said spacer.

10. In a unit mount construction for thermionic discharge devices, ceramic spacers, cathode, grid and anode electrodes positioned between 25 said spacers, and aluminum oxide collars on the anode side rods between the anode and spacers for spacing the anode electrode from said spacers.

11. In a thermionic discharge device, an envelope with a press, a cathode lead-in wire sealed in 30 said press and an electrode assembly comprising two indirectly heated parallel cathode sleeves, heater means in said sleeves connected at one end to said lead-in wire, and means for electrically connecting the ends of the sleeves opposite 35 the ends which are connected to said cathode lead-in wire.

CHARLES W. TAYLOR.
